M. E. APPLEGATE.
RAIL FASTENER AND TIE.
APPLICATION FILED JUNE 19, 1915.

1,163,879.

Patented Dec. 14, 1915.

UNITED STATES PATENT OFFICE.

MILES E. APPLEGATE, OF SUGARLOAF, PENNSYLVANIA.

RAIL FASTENER AND TIE.

1,163,879.

Specification of Letters Patent. Patented Dec. 14, 1915.

Application filed June 19, 1915. Serial No. 35,106.

To all whom it may concern:

Be it known that I, MILES E. APPLEGATE, a citizen of the United States, residing at Sugarloaf, in the county of Luzerne and 5 State of Pennsylvania, have invented certain new and useful Improvements in Rail Fasteners and Ties, of which the following is a specification, reference being had to the accompanying drawings.

10 This invention relates to an improved rail fastener and tie and has for its primary object to provide means for quickly and securely fastening the rails upon the tie to prevent spreading movement of said rails, said 15 means being capable of adjustment which will permit the proper insulating of the rails from the tie when necessary.

It is another object of my invention to provide a metal rail tie of improved construction having anchoring means at its opposite ends which effectively prevents shifting movement of the tie in the rock ballast and also holds the ballast bed in a compact condition and prevents spreading thereof.

25 It is an additional object of my invention to generally improve rail ties and devices of the above character and render the same strong and durable, as well as inexpensive in both the original cost thereof and proper 30 maintenance of the same.

With the above and other objects in view, my invention consists in the novel features of construction, combination and arrangement of parts to be hereinafter more fully 35 described, claimed and illustrated in the accompanying drawing, in which,

Figure 1 is a perspective view of a rail tie showing one rail secured thereon by means of my improved fastener while the other 40 rail has been removed; Fig. 2 is an enlarged longitudinal section; Fig. 3 is a section taken on the line 3—3 of Fig. 2; Fig. 4 is an end elevation of the tie.

Referring in detail to the drawing, 5 designates the metal tie which is of I-shaped form in cross-section, the top and bottom flanges 6 and 7, respectively, being preferably the same width. To the vertical web of this tie, at its opposite ends and on each 50 side thereof, angle plate 8 are secured by means of the rivets, indicated at 9. The transversely and outwardly extending flanges of these angle plates have their outer edges disposed in a plane coincident with 55 the longitudinal edges of the top and bottom flanges 6 and 7 of the tie. The angle plates

8 serve as anchoring means for the tie and hold the same against a longitudinal shifting movement in the rock ballast bed. The flanges of the angle plates also prevent 60 spreading of the rock and hold the bed in compact condition.

In the upper surface of the flange 6 of the tie, adjacent to each end thereof, the spaced series of transversely extending teeth 10 are 65 formed. These teeth are of slightly less length than the width of the tie and the upper edges of the teeth are flush with the top surface of the flange 6. Shoulders 11 are thus produced at the opposite ends of each 70 series of teeth 10. The rails, indicated at R, are adapted to be seated upon the tie between the spaced series of teeth 10.

The fastening plates 12 include relatively heavy body portions 13, upon one end of 75 which the angularly disposed clamping lugs 14 are formed for engagement upon the base flanges of the rail. Upon the bottom face of the body 13 of the fastening plate, a series of teeth, indicated at 15, are formed. 80

These fastening plates are of a width equal to the length of the teeth 10 on the tie. There are a greater number of teeth in each series in the surface of the tie than there are upon the bottom faces of the respective fastener plates, so that said plates may be adjusted longitudinally of the tie. The flange 85 90

6 on each side of the central web of the tie is provided with openings, indicated at 16, in which the fastening bolts 17 snugly fit. 95 These bolts extend through spaced slots 18 formed in the fastening plates and have nuts 19 threaded upon their upper ends. It will thus be seen that the rail fastening plates may be readily adjusted toward or from each other longitudinally of the tie in order to permit the rails to be shimmed or insulating material arranged between the same, the tie and the fastening members. The clamping 100 plates are then forced downwardly so that the teeth thereon will interlock with the teeth 10 on the tie by simply adjusting the nut 19.

From the foregoing description, taken in connection with the accompanying drawing, the construction, manner of use and several advantages of my invention will be clearly and fully understood. The device provides simple and effective means for securely holding the rails against spreading movement and, in view of the fact that the tie is constructed of cast steel or other metal, it will be obvious that the entire device is extremely 105 110

strong and durable. The adjustment of the fastening members may be readily made and the use of spikes or analogous rail securing devices is entirely dispensed with.

5 While I have shown and described the preferred construction and arrangement of the several elements of the device, it will, nevertheless, be understood that the same is susceptible of considerable modification there 10 in, and I, therefore, reserve the privilege of resorting to all such legitimate changes as may be fairly embodied within the spirit and scope of the invention as claimed.

Having thus fully described my invention, 15 what I desire to claim and secure by Letters Patent is:

The combination with a metal rail tie provided in its upper surface with spaced rectangular recesses, each recess having a series 20 of teeth formed upon its base wall extending transversely of the tie and spaced vertical bolt receiving openings extending through the tie plate and the central tooth in each series, the free ends of the teeth being flush

with the upper surface of the tie; of rail 25 fastening members, each provided with a series of teeth on its bottom face intermediate the length thereof for engagement with one of the series of teeth on the tie, the ends of the teeth on said plates abutting 30 against the end walls of the rectangular recesses in the tie plate, whereby the fastening members are held against transverse shifting movement upon the tie, the outer ends of the fastening members overlying the upper surface of the tie, and bolts adapted to be disposed through the vertical openings in the tie plate and through co-inciding openings in said fastening members to securely 35 clamp said members in interlocking engagement with the teeth on the tie plate and upon the base flange of a rail.

In testimony whereof I hereunto affix my signature in the presence of two witnesses.

MILES E. APPLEGATE.

Witnesses:

HARRY EVES,
F. C. JOHNSON.
